US0D1099868S

(12) **United States Design Patent** (10) Patent No.: **US D1,099,868 S**
(45) Date of Patent: ** Oct. 28, 2025

(54) **WIRELESS SPEAKER**

(71) Applicant: **SHENZHEN ZOWEE TECHNOLOGY CO., LTD,**
Guangdong (CN)

(72) Inventors: **Hao Gu**, Guangdong (CN); **Junhui Li**,
Guangdong (CN); **Chunlei Feng**,
Guangdong (CN)

(73) Assignee: **SHENZHEN ZOWEE TECHNOLOGY CO., LTD**, Shenzhen (CN)

(**) Term: **15 Years**

(21) Appl. No.: **29/959,053**

(22) Filed: **Aug. 23, 2024**

(30) **Foreign Application Priority Data**

Feb. 23, 2024 (CN) 202430092664.X

(51) LOC (15) Cl. **14-01**

(52) U.S. Cl.

USPC **D14/221**

CLAIM

The ornamental design for a wireless speaker as shown and described.

DESCRIPTION

FIG. 1 is a front and right side perspective view of a wireless speaker showing our new design;

FIG. 2 is a top, rear and left side perspective view thereof;

FIG. 3 is a rear and right side perspective view thereof;

FIG. 4 is a bottom, front and right side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof; and,

FIG. 10 is a bottom plan view thereof.

1 Claim, 10 Drawing Sheets
